United States Patent

Des. 236,986
Patented Sept. 30, 1975

236,986

PORTABLE COMBINED CONTROL AND DISPLAY CONSOLE

Edward A. Schierholz, Littleton, Colo., assignor to
Honeywell Inc., Minneapolis, Minn.

Filed June 20, 1974, Ser. No. 481,202

Term of patent 14 years

Int. Cl. D14—02

U.S. Cl. D26—5 C

FIG. 1 is a front perspective view of a portable combined control and display console embodying my new design, and

FIG. 2 is a rear perspective view of the console shown in FIG. 1.

I claim:

The ornamental design for a portable combined control and display console, as shown.
